UNITED STATES PATENT OFFICE.

ELIAS GROAT, OF SAN LUIS OBISPO, CALIFORNIA.

APPARATUS FOR REDUCING AND SOFTENING BITUMINOUS ROCK.

SPECIFICATION forming part of Letters Patent No. 502,416, dated August 1, 1893.

Application filed March 25, 1892. Serial No. 426,336. (No model.)

To all whom it may concern:

Be it known that I, ELIAS GROAT, a citizen of the United States, residing at San Luis Obispo, in the county of San Luis Obispo and State of California, have invented certain new and useful Improvements in Apparatus for Reducing and Softening Bituminous Rock; and I do hereby declare that the following is a full, clear, and exact description of my said invention, reference being had to the accompanying drawings, that form part of this specification.

My invention has for its object to produce a portable apparatus for melting and reducing bituminous rock and other similar substances that are being used at the present time as paving material to cover the surfaces of streets and roads; and my improvements consist in certain construction and combination of parts producing an improved portable apparatus for reducing bituminous rock and bringing the material into a suitable soft and disintegrated condition, for making roadways by the aid of heat, produced by steam alone, which does not come in direct contact with the material being reduced, all as hereinafter fully set forth.

Referring to the accompanying drawings which form part of this specification—Figure 1—is a side elevation partly in section of my improved apparatus, mounted upon a wheeled truck, for convenience of moving from place to place as the work progresses. Fig. 2—is a top view of tank. Fig. 3—is a bottom view of tank showing means for discharging the prepared material. Fig. 4—is a view in perspective of a steam stack for the interior of the tank.

This apparatus is specially constructed and adapted for working bituminous rock, a natural substance which is used as a paving material, and which requires to be reduced to a soft and yielding mass by heat, before spreading it upon the roadway. To work this material and produce it in such heated condition on the spot, I have mounted my apparatus on a four-wheeled truck, having the necessary steam boiler for furnishing steam, so that the machine can be moved from place to place as the work progresses.

In carrying out my invention I employ an upright iron tank about ten feet high and six

feet in diameter with double walls for a surrounding steam jacket. The inner wall of this tank A is made conical at the lower ends 55 as at A^x so that the reduced material can be easily and quickly discharged when the sliding gates over the lower end of the tank are operated; these gates consist of two flat plates B B^x which are moved outward and backward between the plates B² B² forming sliding ways, by means of the hand levers C C the inner ends of which are pivoted to the lower plate B² of the runway, and to the sliding gates by the pins C^x C^x, while the outer ends 65 of the levers extend through a slot D, in the frame of the machine, and move in a strap or plate D^x pinned to the under plate B² on that side of the machine.

In order to prevent the material under treatment from packing at the conical end of the tank, I employ a stirrer which consists of a vertical hollow spindle E stepped in a pin a upon the horizontal cross-bar E^x at the foot of the tank. The lower end of the spindle or 75 stirrer is provided with radial arms a^x a^x a^x a^x while the upper end passes up through to the top of the tank or cover, and is operated by a hand-lever or other means as occasion requires.

The stack or coil which I employ in my tank is shown in Fig. 4 and it consists of four upright tubes or pipes F F with horizontal and transverse coupled heads or pipes F^x F^x. Over the ends of these latter pipes or tubes 85 are fitted the segments or curved plates G G, made to conform to the cylindrical condition of the inner wall of the tank, and the whole is made steam-tight. Connection of this stack with the steam jacket of the tank is made 90 near the lower end of the inner wall by union couplings H H^x which permit the steam from the jacket to enter the stack at all times and when the stack is in position a sufficient space for the action of the arms of the stirrer will 95 be had beneath in the chamber or lower end, and the spindle will extend up within the openings at the foot and head of the stack and enter a hole in the guide-plate I, at the top of the tank. This flanged guide-plate I 100 fits down in a ledge between the inner and outer walls of the tank, and a hinged cover J shuts down over all, up through which the operating spindle of the stirrer projects, and

thus the stack having the end curved plates which fit against the wall of the tank, will conform to the curvature thereof; and the spindle stepped in the lower cross-bar and 5 extending up through the guide-plate I and hinged cover, is prevented from side or lateral movement.

Steam is admitted to the steam jacket from the boiler by means of a pipe K, and all 10 sur- plus steam that is not required for heating the material under treatment, is taken from the steam jacket through the pipe L, and con- ducted to an engine, not shown, for driving the elevator M employed for conveying the 15 material to the tank by a belt and pulley connection, while the water of condensation is drawn off through the pipe and cock N, into a tank, to be used in its heated state to sup- 20 ply the boiler.

20 The upwardly extending curved arms O O will afford bearings for the driving shaft of the elevator, and to the lugs P P a platform is connected to sustain the men engaged in 25 operating the machine.

25 In practice the material is conveyed to the tank in suitable quantity by the elevator, and the hinged cover shut down, when steam from the boiler is then admitted to the jacket and stack of pipes, in which condition the 30 great heat generated from the steam will soon reduce the material to a plastic and homoge- neous state, and in condition fit for use with- out any of the material coming in direct contact with the steam. In this condition the 35 sliding gates at the bottom of the tank are opened and the contents of the tank dis- charged, when the gates are closed and a new charge conducted to the tank for reduction; or the charging and discharging may be con- 40 tinuous as the tank is not under pressure.

Should the material under treatment have a tendency to adhere in a mass within the 45 conical chamber at the bottom of the tank, the stirrers are put in motion from the plat- form, by a lever upon the end of the spindle, and all tendency of the material to pack will

be prevented. Thus it will be seen that no steam whatever will come in contact with the material being reduced or under treatment.

Having thus fully described my invention, 50 what I claim, and desire to secure by Letters Patent, is—

1. An apparatus for reducing and preparing bituminous rock consisting of a jacketed or double walled steam-tight tank A, with a 55 conical lower end and horizontally sliding discharge gates at the bottom, and having its interior provided with a vertical steam-tight stack connecting with the lower jacket of the tank, by means of couplings at the lower end, 60 and curved supporting plates at both ends which conform to the interior wall of the tank, as hereinbefore set forth.

2. The combination with an apparatus for reducing and preparing bituminous rock, 65 consisting of a steam jacketed tank with a coni- cal bottom, and its interior provided with a vertical steam-tight stack connecting with the steam jacket, of the vertical stirrer com- posed of radial arms or blades, operating in 70 the lower end of the tank beneath the stack, upon a spindle stepped in a cross-bar at the foot of the tank, as and for the purpose set forth and specified.

3. In an apparatus for reducing and pre- 75 paring bituminous rock for paving purposes, consisting of a double walled steam-tight tank A, steam induction and outlet pipes, pipe N for discharging water of condensation, hinged cover for the reducing chamber, steam-tight 80 stack and stirrer in said chamber, the dis- charge opening in the bottom of said cham- ber, and the sliding doors therefor, all con- structed and arranged substantially in the 85 manner and for the purpose set forth.

In testimony that I claim the foregoing I have hereunto set my hand and seal.

ELIAS GROAT. [L. S.]
